(57) **CLAIM**

The ornamental design for a spiral-wrap golf club grip, substantially as shown and described.

DESCRIPTION

FIG. 1 is a side elevational view of a spiral-wrap golf club grip showing my new design, the view of the opposite side of said grip being similar to the side shown in FIG. 1; FIG. 2 is a top plan view of said grip; FIG. 3 is a bottom view of said grip; and, FIG. 4 is an enlarged view of the encircled area designated 4 in FIG. 1.
